7 Claims

This invention relates to voltage regulators and particularly to voltage regulators incorporating failure detection and protection circuits.

Prior art voltage regulators, failure detectors and protective devices as applied in the telecommunications art have depended generally on combinations of conventional rectifiers, voltage dividers, fuses, relays and the like. None of these have been entirely satisfactory since they have lacked failure monitoring and switchover as well providing uncertain voltage levels, too slow response times, required excessive time for resetting, or the like.

It is, therefore, a primary object of this invention to provide an improved voltage regulator which incorporates features of a failure detector and protection circuit such that it is capable of providing a source of stable voltage while assuring safety and providing warnings in case of failure or partial failure of components in the regulator or in the load.

The foregoing object and others related thereto will be more fully understood from the following description when read in connection with the accompanying drawing which shows a schematic diagram of a preferred embodiment of the invention.

Turning now to the figure for a detailed description of the preferred embodiment of the invention it will be noted that the figure is divided into two parts, one on either side of the vertical dashed line. This vertical line divides the drawing into two nearly identical portions. The portion to the left of the vertical line represents a primary, or principal, voltage regulator and protective device. The portion to the right represents a secondary or stand-by regulator. The stand-by regulator is coupled to the primary regulator in such a way that failure of a component in the primary regulator will automatically cause the stand-by regulator to function.

Turning first to a description of the left hand side of the figure voltage regulation is provided by operation of the Zener diodes D1 and D2. The diodes are shown connected serially from a voltage $-V$ applied on the terminal 6 through the resistor R3 and the contacts of relay R1 to ground at terminal 13. Resistor R3 functions as a dropping resistor and in a preferred embodiment of the invention consisted of a 20 ohm resistor which will drop the voltage $-V$ which is set at -50 volts by approximately 24 volts while the two Zener diodes provide a drop of about 13 volts apiece. As a consequence of the operation of these components, the potential at the first load point 3 in the example is maintained at -26 volts, while that at load point 5 is maintained at -13 volts. These two potentials are made available at terminals 11 and 15 to communication systems or control devices indicated by the block 25, labeled "Load Circuits."

The voltage supplied at terminal 3 is monitored by a bridge circuit including the elements CR1, CR2, CR3, CR4 and a winding of relay R1. The opposite terminal of the bridge at point 7 is initially set at a voltage equal to one half of V which is established by the potential of $-V$ at terminal 4 and a voltage divider made up of equal sized resistors R5 and R6 which in a preferred embodiment have a resistance of 500 ohms each. So long as the potential supply from terminal 3 is nearly equal to that at terminal 7 the bridge will remain in balance and the

2

relay R1 will remain inoperative. However, should either diode D1 or D2 short, the $-1/2$ V volts would become $-1/4$ V volts by operation of the remaining Zener diode. With $-1/4$ V volts, or -13 volts, on one terminal of the bridge, the bridge circuit will become unbalanced causing current to flow through the relay R1 and operating it. Once the relay R1 starts to operate, a preliminary "make" closes and applies ground to the secondary winding to insure complete operation.

When the relay R1 operates it will open the "break" contacts R1 which are shown closed in the figure and close the corresponding "make" contacts. Operation of the R1 contacts will cause a transfer of the load to the stand-by regulator shown to the right of the dashed line. The stand-by regulator will be seen to be identical in its principal components to the original regulator and will function in the same fashion.

Assuming again that the conditions illustrated in the figure prevail and that one of the original Zener diodes D1 or D2 suddenly becomes "open," the potential supplied to the number 3 terminal will rise to about -34 V (or -37 volts) causing an unbalanced condition on the bridge circuit. This in turn will cause the R1 relay to operate changing the position of the "make-break" contacts R1 so that the stand-by regulator will again be placed in control of the potentials to the load circuit.

As indicated previously, the stand-by regulator functions in essentially the same way as the primary regulator. For example, when the "make-break" contacts R1 are operated by the relay R1, terminals 7 and 9, shown as being connectable to a load (not shown), are disconnected from the voltage sources at terminals 3 and 5 and connected instead to the terminals 17 and 23. The voltage available on terminals 17 and 29 are made equal to those provided at respective terminals 3 and 5 by operation of the diodes D3 and D4 in conjunction with a resistor R4 supplied by a potential $-V$ at terminal 26. The same values of resistance and identical diodes may be used in the standby regulator so that it exactly replaces the primary regulator when needed.

If, after the stand-by regulator assumes control of the load voltages there is a failure of either D3 or D4, unbalance will be produced in the bridge circuit associated with this second regulator. This situation will provoke operation of the relay R2 to switch the "make" and/or "break" contacts R2 to their alternate positions, disconnecting the potential $-V$ at terminal 26 from the load terminals 11 and 15 and supplying a signal to an alarm circuit (not shown) over terminals 21. The alarm can be a relay operating a visual signal, an aural signal or some other indicator.

It will be apparent from the figure that in the event of failure in the diodes D1 or D2 the primary fail lamp 9 will be lighted through the application of voltage at terminal 8 through the contact R1 to ground. Likewise, if there is a failure of the secondary or stand-by regulator the secondary fail lamp 19 will be operated over the terminal 28 and the corresponding "make" contact R2.

While the principles of the invention have been described above in connection with specific apparatus and applications, it is to be understood that this description is made only by way of example and not as a limitation on the scope of the invention.

What is claimed is:

1. A voltage regulator incorporating a protection and warning circuit, comprising:
a first terminal upon which a voltage is applied,
a second terminal at ground potential,
means for dividing said voltage into two lower voltages
for supply to a load circuit,

3

said means including a resistor and two Zener diodes coupled in series between said first terminal and said second terminal, means supplying a reference potential, a bridge circuit connected to sense one of the two lower voltages and compare it with said reference potential, and means responsive to imbalance in said bridge circuit to disconnect said two lower voltages from said load circuit.

2. A voltage regulator substantially as claimed in claim 1, in which:

said means responsive to imbalance in said bridge includes a relay having "break" contacts for disconnecting said two lower voltages from said load circuit.

3. A voltage regulator substantially as claimed in claim 1, in which:

said means supplying a reference potential includes a source of voltage and a voltage divider.

4. A voltage regulator substantially as claimed in claim 1, in which:

a second voltage regulator essentially identical to that of claim 1 is made available, said means for disconnecting said two lower voltages from said load circuit includes means for connecting said second voltage regulator to said load circuit, and said second voltage regulator includes means for supplying desired voltages to said load circuit.

5. A voltage regulator substantially as claimed in claim 4, in which:

the second voltage regulator includes means responsive to imbalance of a bridge circuit, and

said means responsive to imbalance of a bridge circuit includes means for supplying a signal to operate an alarm in the event of failure of said second voltage regulator.

6. A voltage regulator substantially as claimed in claim 5, in which:

said means responsive to imbalance of a bridge circuit includes means for disconnecting said regulator from said load circuit.

7. A voltage regulator substantially as claimed in claim 1, in which:

said means responsive to imbalance in said bridge circuit includes means to operate a light indicating failure of the voltage regulator.
